(57) **CLAIM**

The ornamental design for a receptacle for carnival favors,
as shown and described.

DESCRIPTION

FIG. 1 is a perspective view of my new ornamental design
for a receptacle for carnival favors.

FIG. 2 is a top view thereof.

FIG. 3 is a bottom view thereof.

FIG. 4 is a side view thereof, the opposite view being a
mirror image of the view of FIG. 4.

FIG. 5 is a front view thereof; and,

FIG. 6 is a rear view thereof.

The broken line showing of environmental structure is for
illustrative purposes only and forms no part of the claimed
design.
